(57) **CLAIM**

The ornamental design for a phone or tablet stand with speaker, as shown and described.

DESCRIPTION

FIG. 1 is a perspective view of a phone or tablet stand with speaker showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of portion 9 shown in FIG. 1;

FIG. 10 is a perspective view thereof, but shown in a first position of use;

FIG. 11 is a perspective view thereof, but shown in a second position of use; and,

FIG. 12 is a perspective view thereof, but shown in a third position of use.

The dash-dash broken lines in the drawings depict portions or environment of the phone or tablet stand with speaker that form no part of the claimed design. The dot-dash broken lines represent boundaries of the enlarged portion and form no part of the claimed design.
